SAFETY DEVICE FOR WINDOWS

Benjamin Harrison Pollock, Jenkintown, Pa.

Application February 3, 1939, Serial No. 254,486

9 Claims. (Cl. 20—72)

This invention relates to window-cleaners' safety devices for windows, and, more particularly, to means for attaching safety belts for window-cleaners to the frames of windows, and is a continuation in part of my prior application Serial No. 209,116 filed May 20, 1938, for "Safety device for windows."

An important object of my invention is to provide a construction which is entirely free from unsightly projections or knobs such as are ordinarily employed in such windows, thereby economizing space in the shipment of metallic windows and promoting the esthetic appearance of windows of all types.

Another and important object of my invention is to provide a construction such that the loads imposed upon the frame by the window-cleaner are, either in case of emergency or in ordinary operation, borne by a metallic element of the window itself and not by a member attached to the outer surface thereof through connecting means such as are ordinarily employed.

A still further object of the invention is to provide a construction such that an extended attaching surface may be provided without in any way detracting from the appearance of the window.

Another object of the invention is the provision of a safety structure for metallic windows which may be installed at the factory, which will not in any way interfere with flat packing and storage of the windows, and will not offer projecting portions which might be damaged or damage other windows when the windows are in transit or during handling thereof.

Another object of the invention is to afford a safe and inconspicuous attachment for wooden-framed windows without the necessity of employing through-bolts.

These and other objects I attain by the construction shown in the accompanying drawings wherein, for the purpose of illustration, I have shown a preferred embodiment of my invention and wherein:

Fig. 1 is a perspective view showing a safety device constructed in accordance with my invention applied to a metallic window frame;

Fig. 2 is a sectional view illustrating its adaptation to a wooden sash;

Fig. 3 is a section on line 3—3 of Fig. 1;

Fig. 4 is a fragmentary perspective of the window frame element showing the opening provided for the safety belt terminal;

Fig. 5 is a perspective view of the safety belt terminal;

Fig. 6 is a perspective view of the internal casting element;

Fig. 7 is a perspective view partially in section showing the safety belt terminal engaged in the opening;

Fig. 8 is a vertical sectional view through the window-applied structure of the safety device;

Fig. 9 is a vertical sectional view similar to that shown in Fig. 8 but illustrating a modified construction;

Fig. 10 is a section on line 10—10 of Fig. 9; and

Fig. 11 is a perspective view of the belt terminal illustrated in Figs. 9 and 10.

In accordance with my invention, a vertically extending metallic element fixedly secured to the window is provided with a vertically elongated keyhole slot. This metallic element can either comprise an actual part of the frame of the window, as in the case of metallic sash, as indicated at 10, or may comprise an elongated Z-iron 11 fitted to the frame 12 of a wooden sash. When the construction of Fig. 2 is employed, the Z-iron is made of such length as will provide adequate strength, and it will be obvious that the projection of the inner flange behind the frame 12 will securely anchor this member in position. Slot 13 is made of considerable length, and against the inner surface of the metallic element is arranged a similarly slotted casing 14 having sealing engagement with the metallic element about the edges of the slot, as indicated at 15. The casing is arranged with the lower end of its slot coincident with the lower end of the slot of the metallic frame element of the window and has its lower wall sloping downwardly, as at 16, so that any rain water which may enter the slot will be shed therefrom and pass to the exterior of the metallic element. Obviously, any other suitable means may be provided to insure proper drainage.

The casing 14 has an opening, similar to that of the metallic element, and is adapted to receive through its enlarged upper end 17 an elongated head element 18 of a terminal 19 for the safety belt 20, the narrow portion 21 of the slot being adapted to receive the restricted neck 22 of the terminal.

Upon the outer surface of the metallic element I preferably pivot a cover 23, and this cover is, preferably, made in two hingedly connected sections 23a, 23b, of which the section 23a is pivoted at the upper end of the opening 13 and is of sufficient length to cover such portion of that opening as will prevent the elongated head 55

18 of the belt terminal from being withdrawn from the enlarged portion 17 of the slot when the section 23a depends from its pivotal support. A spring and cam latch 23c may be used to hold 5 the section 23b in its several positions. This construction will ordinarily prevent the entrance of rain water to the casing, and will hide the slot from view in addition to its function in preventing withdrawal of the safety device. Attention is directed to the fact, however, that 10 due to the elongation of the head and the fact that the shank and connecting neck of the belt terminal extend downwardly at an angle from the head, there will be a distinct tendency of the head to bind during attempts to move the same 15 vertically unless the movement is directly vertical and not only partially so.

In the form of the invention illustrated in Figs. 9 to 11, the window structure is substantially 20 identical with that shown in the remaining figures; the only modification being the use of a reinforcing plate 24 to form the slot defining portions of the casing 14a, this plate being enlarged to provide a greater anchorage surface 25 about the edges of the slot in the window and frame 18. The principal modification lies in the belt terminal 19a which is shown as provided with an improved latching means to prevent accidental displacement of the terminal from the slot. The 30 latch comprises a pivoted lever 25 which is urged to the position shown in solid lines in Fig. 9 by the spring 26 and has its movement in this direction limited by a stop pin 27 extended through the flanged side arms 28 of the lever. This latch, 35 when in the position shown in solid lines in Fig. 9, has its inner end disposed above the head 18 of the terminal and in substantial alignment therewith at a point such that upon vertical movement of the terminal 19a it will come into contact with the upper wall of the slot prior to 40 disengagement of the head 18 from the narrow portion of the slot, thus absolutely preventing accidental disengagement of the head. However, by a slight pressure of the palm of the hand 45 against the outer end of the lever it may be swung to the dotted line position of Fig. 9 and in this position will clear the front wall or frame permitting the head to be elevated to its disengaging position, and removed from the frame in one 50 movement.

It will be obvious that the engagement of the vertical head behind the metallic element of the window places the strain entirely on the window itself and distributes this strain over a relatively 55 wide surface instead of concentrating it at a pair of securing elements such as are ordinarily employed in fastening the usual knob plates to the window frame. This is particularly true when the internal housing or casing 14 is utilized, since 60 this housing will, of itself, serve to assist in distribution of the strains. Furthermore, with the use of a relatively long head on the belt terminal the wear due to the constant movement of this terminal is distributed over a greater area and 65 will not result in rapid destruction thereof as in the case of the ordinary terminal. Furthermore, since the anchor serving as the belt terminal is subject to constant inspection by the operator, dangers arising from disintegration by crystallization or fracture are considerably lessened. 70

While I have disclosed my invention as applied to only one type of wooden sash frame and a single type of metallic sash frame, it will be obvious that it is readily adapted to use with all types of sash and I, accordingly, do not wish to be under-

stood as limiting myself to either form herein particularly illustrated except as hereinafter claimed.

I claim:

1. In combination with a window structure including a fixed, vertically extending metallic element having a vertically elongated keyhole slot and arranged to afford a recess at the slot, a safety belt terminal having an elongated head insertible through the upper larger end of the slot and of a width greater than the width of the narrow lower portion of the slot, a vertically elongated narrow neck engageable in the lower narrow portion of the slot, and a cover pivoted to said metallic element at the upper end of the slot and normally concealing said slot. 10

2. In combination with a window structure including a fixed, vertically extending metallic element having a vertically elongated keyhole slot and arranged to afford a recess at the slot, a safety belt terminal having an elongated head insertible through the upper larger end of the slot and of a width greater than the width of the narrow lower portion of the slot, a vertically elongated narrow neck engageable in the lower narrow portion of the slot, and means pivoted at the upper end of the slot for normally blocking the upper larger end of the slot. 20

3. In combination with a window structure including a fixed, vertically extending metallic element having a vertically elongated keyhole slot and arranged to afford a recess at the slot, a safety belt terminal having an elongated head insertible through the upper larger end of the slot and of a width greater than the width of the narrow lower portion of the slot, a vertically elongated narrow neck engageable in the lower narrow portion of the slot, and means pivoted at the upper end of the slot for normally blocking the upper larger end of the slot comprising a cover 30 formed in hinged connected sections, the upper portion of which is of a length to cover the upper end of the slot. 35

4. In combination with a window structure including a fixed, vertically extending metallic element having a vertically elongated keyhole slot and arranged to afford a recess at the slot, a safety belt terminal having an elongated head insertible through the upper larger end of the slot and of a width greater than the width of the narrow lower portion of the slot, a vertically elongated narrow neck engageable in the lower narrow portion of the slot, and a casing at the inner surface of the metallic element and having sealing engagement with the metallic element 50 about the edges of the slot. 55

5. In combination with a window structure including a fixed, vertically extending metallic element having a vertically elongated keyhole slot and arranged to afford a recess at the slot, a safety belt terminal having an elongated head insertible through the upper larger end of the slot and of a width greater than the width of the narrow lower portion of the slot, a vertically elongated narrow neck engageable in the lower narrow portion of the slot, a latch pivoted to the upper portion of said terminal, means limiting pivotal movement of the latch with its inner end spaced above and in alignment with said head at a point such that said inner end will engage the upper 70 end of the slot prior to disengagement of the head from the narrow portions of the slot, and a spring yieldably maintaining said latch in said position. 60

6. In combination with a metallic window sash 75

frame having a vertically extending portion thereof formed with a vertically elongated key-hole slot opening to the interior of the frame, a safety belt terminal having an elongated head insertible through the upper larger end of the slot and of a width greater than the width of the narrow portion of the slot, a vertically elongated narrow neck engageable in the lower portion of the slot, a latch pivoted to the upper portion of said terminal, means limiting pivotal movement of the latch with its inner end spaced above and in alignment with said head at a point such that said inner end will engage the upper end of the slot prior to disengagement of the head from the narrow portion of the slot, and a spring yieldably maintaining said latch in said position.

7. In combination with a window structure including a fixed, vertically extending metallic element having a vertically elongated keyhole slot and arranged to afford a recess at the slot, a safety belt terminal having an elongated head insertible through the upper larger end of the slot and of a width greater than the width of the narrow lower portion of the slot, a vertically elongated narrow neck engageable in the lower narrow portion of the slot, a cover pivoted to the upper end of the slot and normally concealing said slot, a latch pivoted to the upper portion of said terminal, means limiting pivotal movement of the latch with its inner end spaced above and in alignment with said head at a point such that said inner end will engage the upper end of the slot prior to disengagement of the head from the narrow portion of the slot, and a spring yieldably maintaining said latch in said position.

8. In combination with a window structure including a fixed, vertically extending metallic element having a vertically elongated keyhole slot

and arranged to afford a recess at the slot, a safety belt terminal having an elongated head insertible through the upper larger end of the slot and of a width greater than the width of the narrow lower portion of the slot, a vertically elongated narrow neck engageable in the lower narrow portion of the slot, means pivoted at the upper end of the slot for normally blocking the upper larger end of the slot, a latch pivoted to the upper portion of said terminal, means limiting pivotal movement of the latch with its inner end spaced above and in alignment with said head at a point such that said inner end will engage the upper end of the slot prior to disengagement of the head from the narrow portion of the slot, and a spring yieldably maintaining said latch in said position.

9. In combination with a window structure including a fixed, vertically extending metallic element having a vertically elongated keyhole slot and arranged to afford a recess at the slot, a safety belt terminal having an elongated head insertible through the upper larger end of the slot and of a width greater than the width of the narrow lower portion of the slot, a vertically elongated narrow neck engageable in the lower narrow portion of the slot, a casing at the inner surface of the metallic element and having sealing engagement with the metallic element about the edges of the slot, a latch pivoted to the upper portion of said terminal, means limiting pivotal movement of the latch with its inner end spaced above and in alignment with said head at a point such that said inner end will engage the upper end of the slot prior to disengagement of the head from the narrow portion of the slot, and a spring yieldably maintaining said latch in said position.

BENJAMIN HARRISON POLLOCK.
